US0D1104363S

(12) **United States Design Patent** (10) **Patent No.:** **US D1,104,363 S**
(45) **Date of Patent:** **** Dec. 2, 2025**

(54) **SAFETY PLATE FOR A HARNESS**

(71) Applicant: **Honeywell Safety Products USA, Inc.**,
Charlotte, NC (US)

(72) Inventors: **Zheng Gu**, Shanghai (CN); **Wenbo Wang**, Shanghai (CN); **Ling Lin**, Shanghai (CN); **Peng Zhou**, Shanghai (CN)

(73) Assignee: **Honeywell Safety Products USA, Inc.**,
Latham, NY (US)

(**) Term: **15 Years**

(21) Appl. No.: **29/976,889**

(22) Filed: **Dec. 4, 2024**

Related U.S. Application Data

(62) Division of application No. 29/867,739, filed on Nov. 7, 2022, now Pat. No. Des. 1,071,380.

(57) **CLAIM**

The ornamental design for a safety plate for a harness as shown and described.

DESCRIPTION

FIG. 1 is a perspective view of an embodiment of a safety plate for a harness showing our new design, shown in a position of use with a front plate attached to a back plate; FIG. 2 is a front elevation view thereof; FIG. 3 is a rear elevation view thereof; FIG. 4 is a bottom plan view thereof; FIG. 5 is a top plan elevation thereof; FIG. 6 is a right side elevation view thereof; FIG. 7 is a left side elevation view thereof; FIG. 8 is an exploded perspective view thereof; FIG. 9 is an exploded bottom plan view thereof; and FIG. 10 is an exploded right side elevation view thereof. FIG. 11 is a perspective view of another embodiment of a safety plate for a harness showing our new design, shown in a position of use with a front plate attached to a back plate; FIG. 12 is a front elevation view thereof; FIG. 13 is a rear elevation view thereof; FIG. 14 is a bottom plan view thereof; FIG. 15 is a top plan elevation thereof; FIG. 16 is a right side elevation view thereof; FIG. 17 is a left side elevation view thereof; FIG. 18 is an exploded perspective view thereof; FIG. 19 is an exploded bottom plan view thereof; and, FIG. 20 is an exploded right side elevation view thereof.

(Continued)

The broken lines illustrate portions of the safety plate for a harness that form no part of the claimed design.
